MACHINE FOR DRYING LIQUIDS.

1,302,786.

Specification of Letters Patent.

Patented May 6, 1919.

Application filed November 10, 1917. Serial No. 201,278.

To all whom it may concern:

Be it known that I, ALBERT GLIDIE, a subject of the King of Norway, residing at Håkonbol, Värmland, Sweden, have invented certain new and useful Improvements in Machines for Drying Liquids; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

The present invention has for its object a machine for drying liquids of the kind in which the liquid is dried on the surface of a rotating body, the interior of which is heated by means of steam, hot air or the like.

In accordance with the invention the drying takes place on the plane upper surface of a hollow annular body rotating on a vertical axis, and the upper side of which is inclosed in an annular hood, which forms together with the plane drying surface a closed channel through which passes a stream of hot dry air. The liquid to be dried is fed to the surface in the usual manner by means of a stationary hopper, the open lower end of which is placed at such a distance from the surface, that a suitable layer of liquid is transferred to the surface during its passage below the hopper. Immediately in front of the hopper is placed a stationary scraper for removing the dried product.

On the drawings:

Figure 1 is an axial section through a form of the invention.

Fig. 2 is a side view and

Fig. 3 a plan of the machine.

The hollow annular body 1 with the horizontal drying surface 2 is fastened by means of spider 3 to a rotating vertical shaft 4. Through this shaft heating medium is supplied by means of a channel 5 and tube 6 and let out by means of inlet tube 7 and channel 8.

Over the largest part of its circumference the annular body 1 is covered by a stationary annular hood 9, which incloses tightly the sides of the annular body. Between the upper side 2 of annular body 1 and hood 9 is formed an annular channel 10.

On its underside the body 1 is inclosed in a vessel 11 and a top-plate 12 covers the central opening of hood 9. The liquid to be dried is fed to the surface 2 from a hopper 13, the bottom of which is located at such a distance from surface 2 that a suitable layer of liquid is transferred to the surface during the passage of the same below the hopper.

Immediately after its passage under the hopper the surface enters channel 10 and the drying process begins. In front of hopper 13 is located a scraper 14 for removing the drying product from the surface after the same has passed the whole of the drying channel.

The air in vessel 11 is heated by means of the annular body 1 and is sucked through tube 15 into annular channel 10 near the outlet end of the same, and from this point the air is sucked through the channel by means of exhaust tube 16, which is connected to an evacuator or the like, not shown on the drawing.

By the apparatus above described the heat of the drying medium is utilized in the best possible manner by having the hollow drying body completely inclosed in a vessel so that the heat radiating from the drying body may be utilized for heating the air in said vessel and finally for drying the liquid placed on the drying surface of the hollow drying body.

The drying apparatus above described is particularly adapted for the drying of fluids such as milk and the like, the drying of which may take place in one single operation without any preheating.

However the feeding hopper 13 may also be utilized as a preheating tank, part of the liquid evaporating in the same. In the latter case the feeding hopper is formed as a closed tank and subjected to vacuum being at the same time provided with a suitable stirring apparatus.

I claim:

1. A machine for drying liquids, comprising a hollow annular body rotatable on a vertical axis, means for supplying a heating medium to the interior of said body, a vessel inclosing said body and heated by the latter, means to supply heated air from the vessel to the interior of said body, means to supply liquid to be dried to said body, and

means to draw the heated air through the body in a direction opposite to the direction of movement of the latter.

2. A machine for drying liquids comprising an annular channel rotatable on a vertical axis, a drying plate in the channel, means for supplying a heating medium between the plate and the bottom of the channel, a vessel inclosing the channel and heated by the latter, means to conduct heated air from the vessel to the channel, and means to feed liquid to be dried onto the plate.

3. A machine for drying liquids comprising an annular channel rotatable on a vertical axis, a drying plate in the channel, means for supplying a heating medium between the plate and the bottom of the channel, a vessel inclosing the channel and heated by the latter, means to conduct heated air from the vessel to the channel above the drying plate, and means to feed liquid to be dried onto the plate.

4. A machine for drying liquids comprising a stationary vessel, an annular heated channel rotatable therein, a stationary cover common to said vessel and channel and having a feed and discharge opening at one point, said vessel acting as a heater for air, a hot air connection between said vessel and channel near the discharge side of said opening, and an air discharge from the feed side

of said opening, whereby heated air from the vessel will be caused to flow around said annular channel counter to the direction of movement of the material.

5. A machine for drying liquids comprising a stationary vessel, an annular channel mounted to rotate therein on a vertical axle, an annular rotatable drying plate mounted in the channel above the bottom thereof and forming an annular heating chamber, a heat inlet pipe and an outlet pipe communicating with the chamber through the axle, a stationary annular cover for the channel forming a closed drying chamber, a top-plate for the vessel resting on the channel cover, a feed hopper communicating with the channel above the plate, a heat conduit connecting the vessel with the channel above the plate on one side of the hopper and a heat exhaust conduit communicating with the channel above the plate on the other side of the hopper.

In testimony that I claim the foregoing as my invention I have signed my name in presence of two subscribing witnesses.

ALBERT GLIDIE.
